Attorney.

UNITED STATES PATENT OFFICE.

MARTIN L. STOWE, OF WORCESTER, MASSACHUSETTS.

SHOE.

SPECIFICATION forming part of Letters Patent No. 300,526, dated June 17, 1884.

Application filed April 29, 1884. (No model.)

To all whom it may concern:

Be it known that I, MARTIN L. STOWE, a citizen of the United States, residing at Worcester, in the county of Worcester and State 5 of Massachusetts, have invented certain new and useful Improvements in Shoes; and I declare the following to be a description of my said invention sufficiently full, clear, and exact to enable others skilled in the art to which 10 it appertains to make and use the same, reference being had to the accompanying drawings, which form a part of this specification.

The object of my present invention is to construct a shoe in such manner as to obtain the 15 proper curvature at the back without the usual seam throughout the center of the back, and also without the necessity of crimping the leather at that position, and to arrange the parts in such manner that the leather and 20 seaming will not be strained and broken by the bending of the leather above the counter by the action of the ankle, thus rendering the shoe more durable, better fitting, and more comfortable for the wearer.

25 To this end my invention consists in a shoe-upper composed of parts formed and arranged as herein illustrated and described.

In the drawings, Figure 1 shows the form of pieces employed in making the quarter or rear 30 portion of the upper. Fig. 2 is a perspective view of the shoe. Fig. 3 is a side view of the upper, with diagram-lines illustrating the constructive relation of the parts.

In the construction of my improved shoe- 35 upper the sides or top pieces, A, are cut narrower than the full dimension of the ankle, and are made of the form shown. The foxings B, or lower parts of the quarter for both sides, are formed in a single piece with the central back 40 extension, B', that reaches to the top of the shoe. The back extension, B', is made with parallel sides a a nearly down to the wing portions B², and the edges are then curved outward to meet the top lines, d d, of the foxing- 45 wing portions, with short rounded curves, as at b. The parts A have a curvature along their bottom edges, d', to match the curve or seaming-line d along the top of the foxing- 50 wings B², while the back edges, a', of said parts A are shaped with a curvature corresponding to that required for the heel or back

of the upper. The curve at b' between the back line, a', and bottom line, d', is made similar to that at b on the part B; but the lines a' and d' include a greater angle than the lines 55 a and d, so that when the seams are closed together at S the extended portion B' is thrown backward at the top, in the manner illustrated in Fig. 3, in accordance with the angularity and curvature of the lines a' in relation to the 60 lines d', or as required for fitting the ankle of the wearer above the heel. The seams s are located along the side of the ankle at that position where, on the person, occurs a slight depression occasioned by the rounding in of 65 the sides of the heel-tendons, and at which position the seams will not be liable to occasion inconvenience to the wearer.

The line x x on Fig. 3 and the dotted lines B' indicate the position in which the back of 70 the foxing-piece B would lie if folded flat together along its center line, x' x', and the full lines show the actual position into which the upward-extended portion B' is carried by the closing together of the seams s. The seams s, 75 which unite the parts, may be stitched flat, stitched through the edges, and turned, or in other convenient or desired manner.

By forming and uniting the parts A and D, as shown, a slight degree of fullness is given 80 to the leather at the center of the back at the position m, or bending-point, so that when the toe is raised or the ankle is carried forward, as in Fig. 2, the action does not cause a strain upon the shoe at that position, and the reverse 85 action does not cause the seams to buckle or fold at the top edge of the counter. A small triangular section is cut from the lower central portion of the piece B, as shown at F, Fig. 1, and the edges f f are closed together 90 to give the short inward curvature at the heel. This seam does not extend to the top of the counter, and is not, therefore, subjected to any strain by the bending of the leather. The vamp or fore part G may be of the ordinary 95 form and stitched to the tops and foxings in the usual manner.

What I claim as of my invention, and desire to secure by Letters Patent, is—

1. In a shoe-upper, the back or foxings 100 formed in a single piece with the upward-extending portion B', side wings, B² B², and the

central notch or cut-away section, F, at the lower edge thereof, substantially as and for the purpose set forth.

2. A shoe having an upper constructed substantially as hereinbefore described, with the central upward-extended back portion and side foxings formed in a single piece, with seaming edges shaped as at *a b d*, in combination with side or top pieces, A, shaped as

shown, and having their edges *a' b' d'* fitted to and stitched to said back and foxings, in the manner set forth.

Witness my hand this 26th day of April, A. D. 1884.

MARTIN L. STOWE.
